D. M. LITTLEJOHN,
SURGICAL NEEDLE,
APPLICATION FILED JUNE 24, 1920.

1,377,359.

Patented May 10, 1921.

UNITED STATES PATENT OFFICE.

DANA M. LITTLEJOHN, OF PANA, ILLINOIS.

SURGICAL NEEDLE.

1,377,359.

Specification of Letters Patent. Patented May 10, 1921.

Application filed June 24, 1920. Serial No. 391,390.

To all whom it may concern:

Be it known that I, DANA M. LITTLEJOHN, a citizen of the United States, residing at Pana, in the county of Christian and State 5 of Illinois, have invented certain new and useful Improvements in Surgical Needles, of which the following is a specification, reference being had to the accompanying drawings.

10 This invention relates to surgical needles and more particularly to a needle of this type adapted for use without the assistance of needle holders and forceps.

An important object of the invention is 15 to provide a needle of the above character which when laid upon a table will always present an upstanding grasping surface by means of which it may be readily picked up.

This object I accomplish by forming a 20 needle with semi-circular bends at each end thereof, one of the ends being provided upon the extremity thereof with a piercing point and the other end being provided with an eye for the reception of sewing thread. The 25 semi-circular bend formed in the device will be of sufficient size to allow the grasping thereof by the fingers, the fingers being placed within the bend. In the use of ordinary needles the use of holders and forceps is necessary and as is well known the 30 roughened surfaces of the forceps cause corrugations to form on the side of the needle which render each successive stitch more difficult to perform.

35 A further object of the invention is to provide a surgical needle wherein the initial incision of the needle is accomplished by pulling instead of pushing the needle and in which the pulling motion may be accomplished when the portion of the needle 40 grasped by the fingers is practically parallel with the surface in which the stitch is being taken thereby allowing resting of the hand during such initial movement and accomplishment of the initial incision. It 45 is well known that in forcing the needle in the initial movement of the stitch, with the ordinary type of needle where the initial incision is accomplished by pressure, the action of the muscles of the upper arm are 50 brought into play and consequently are difficult to check when the point of the needle passes through the outer skin. This is especially true in closing surface incisions.

55 A further object of the invention is to provide a needle of this type having, ad-

jacent the eye thereof, a tapered enlargement terminating at the eye in an abrupt reduction forming a shoulder. This enlargement opens the incision made by the point 60 or lance end of the needle sufficiently to permit the sewing thread or suture to pass therethrough without binding.

A further object of the invention is to 65 provide a surgical needle which may be used for sewing either surface incisions or in any deep incision where the fingers may be admitted and the construction of which is such that in pulling the needle through the tissues, the form thereof causes the same to 70 so rotate in the fingers as to be in position to be immediately used in taking the following stitch.

These and other objects I accomplish by 75 means of the needle shown in the accompanying drawings, wherein like numerals designate like parts throughout, and wherein:

Figure 1 is a side elevation of my needle.

Fig. 2 is a similar elevation thereof taken at an angle of 90 degrees to the elevation 80 shown in Fig. 1.

Fig. 3 is an end elevation thereof showing the manner in which the needle rests upon a flat surface.

Fig. 4 shows the initial operation in starting a stitch.

Fig. 5 shows a stitch partially completed, the one end of the needle having passed through both sides of the wound, and

Fig. 6 shows a stitch practically completed.

Referring now more particularly to the drawings, the numeral 10 indicates the body or central portion of my needle. One end of the body portion is provided with a semi-circular bend 11 of sufficient size to accommodate one or more of the fingers of the hand. The free end of the bend 11 is provided with a piercing point 12 or the like.

The opposite end of the body portion 10 100 is provided with a similarly curved semi-circular bend 13 terminating at its end in an eye 14 for the reception of the sewing thread. The bend 13 is arranged at an angle to the bend 11 and preferably at a right angle 105 thereto. Adjacent the eye 14, the body of the bend 13 is provided with a tapered enlargement 15 which terminates abruptly at the eye 14 in a shoulder 16 directed toward the eye. This construction enables the enlargement of the aperture formed of the piercing member or lance 12 sufficiently to

permit the passage of the suture without binding.

In the use of my needle, in starting the same the fingers are inserted in the semi-circular bend 13 and the point 12 passed through the sides of the wound which are to be closed, the needle being pulled. When the bend 11 has been completely passed through the sides of the wound, this bend 10 is then grasped by the fingers and the needle rotated through an angle so as to properly aline the bend 13 with the stitch openings, when the bend may be drawn through the stitch openings, as illustrated by the 15 successive steps shown in the drawings. It will be noted that when the stitch is completed the lance point 12 is in the proper position for engagement with the edge of the incision to form the next stitch having 20 moved through a complete cycle and being positioned at a point alined with the initial incision of the previous stitch and spaced therefrom. While I have illustrated and described my needle as being used for closing surface incisions it is, of course, understood that the needle may be readily operated within any incision which is sufficiently 25 large to permit admission of the fingers.

I am aware that there are surgical needles 30 provided at each end with a bend and in which the bends are arranged at right angles. These bends are, however, not of sufficient length to form a finger receiving hook such as is formed by the semi-circular bend 35 of my needle, and consequently grasping the ends of these needles by the hand is practically impossible. While I have stated above that the bends 11 and 13 are semi-circular it is to be understood that it is not necessary 40 that the same should form a complete semi-circle as it is only necessary that they be continued sufficiently to form a finger receiving hook and that the piercing point 12 should lie parallel to, or approximately par- 45 allel to the body portion of the needle in order that said piercing point may be started by a pull upon the needle.

Other changes, of a similar character, being possible in the construction of my device, I do not limit myself to the specific 50 construction hereinbefore set forth, but may make any such changes, without departing from the spirit of the invention or the scope of the subjoined claims.

55 Having now described my invention, what I claim is:

1. In a surgical needle a body portion provided upon its ends with finger receiving hooks, one of said hooks being provided with 60 a piercing point and the other of said hooks being provided with an eye.

2. In a surgical needle a body portion provided upon its ends with finger receiving hooks of the same and uniform curvature, 65 one of said hooks being provided with a

piercing point and the other of said hooks being provided with an eye.

3. In a surgical needle a body portion provided upon its ends with semi-circular bends forming finger receiving hooks, one of 70 said hooks being provided with a piercing point and the other of said hooks being provided with an eye.

4. In a surgical needle a body portion provided upon its ends with finger receiving 75 hooks, one of said hooks being provided with a piercing point and the other of said hooks being provided with an eye, said hooks being in planes disposed at an angle.

5. In a surgical needle a body portion 80 provided upon its ends with semi-circular bends forming finger receiving hooks, one of said hooks being provided with a piercing point and the other of said hooks being provided with an eye, said hooks being in planes 85 disposed at an angle.

6. In a surgical needle a body portion provided upon its ends with finger receiving hooks, one of said hooks being provided with a piercing point and the other of said 90 hooks being provided with an eye, said hooks being disposed in planes at right angles to one another.

7. In a surgical needle a body portion provided upon its ends with finger receiving 95 hooks of the same and uniform curvature, one of said hooks being provided with a piercing point and the other of said hooks being provided with an eye, said hooks being disposed in planes at right angles to one 100 another.

8. In a surgical needle a body portion provided upon its ends with finger receiving hooks, one of said hooks being provided with a piercing point and the other of said 105 hooks being provided with an eye, said piercing point being directed in the general direction of the loop provided with the eye.

9. In a surgical needle a body portion provided upon its ends with finger receiving 110 hooks of the same and uniform curvature, one of said hooks being provided with a piercing point and the other of said hooks being provided with an eye, said piercing point being directed in the general direction 115 of the loop provided with the eye.

10. In a surgical needle a body portion provided upon its ends with semi-circular bends forming finger receiving hooks, one of 120 said hooks being provided with a piercing point and the other of said hooks being provided with an eye, said piercing point being directed in the general direction of the loop provided with the eye.

11. In a surgical needle a body portion 125 provided upon its ends with finger receiving hooks, one of said hooks being provided with a piercing point and the other of said hooks being provided with an eye, said hooks being in planes disposed at an angle, 130

said piercing point being directed in the general direction of the loop provided with the eye.

12. In a surgical needle a body portion provided upon its ends with finger receiving hooks of the same and uniform curvature, one of said hooks being provided with a piercing point and the other of said hooks being provided with an eye, said hooks being disposed in planes at right angles to one another, said piercing point being directed in the general direction of the loop provided with the eye.

13. In a surgical needle, a body portion provided upon its ends with finger receiving hooks, one of said hooks being provided with a piercing point and the other of said hooks being provided with an eye, the body of the needle adjacent said eye being provided with a tapered enlargement terminating next adjacent the eye in an abrupt shoulder.

14. In a surgical needle, a body portion provided upon its end with finger receiving hooks, one of said hooks being provided with a piercing point and the other of said hooks being provided with an eye, the material of the needle adjacent said eye being

provided with a tapered enlargement terminating in an abrupt shoulder disposed toward said eye, said hooks being disposed in planes at an angle to one another.

15. In a surgical needle, a body portion provided upon its ends with finger receiving hooks, one of said hooks being provided with a piercing point and the other with a tapered enlargement terminating in an abrupt shoulder forming a reduction, said reduction being provided with an eye, said piercing point being directed in the same general direction of the loop with the eye.

16. In a surgical needle, a body portion provided upon its ends with finger receiving hooks of the same and uniform curvature, one of said hooks being provided with a piercing point and the other of said hooks being provided with an enlargement terminating in a shoulder forming a reduction, said reduction being provided with an eye, said hooks being disposed in planes at right angles to one another and said piercing point being directed in the general direction of the loop provided with the eye.

In testimony whereof I hereunto affix my signature.

DANA M. LITTLEJOHN.
